[57] CLAIM

The ornamental design for a container body for liquids and the like, as shown and described.

DESCRIPTION

FIG. 1 is a top plan view of a container body for liquids and the like, showing my design;

FIG. 2 is a front elevation thereof, the opposite side being a mirror image of the front elevation shown;

FIG. 3 is a left side elevation thereof; and,

FIG. 4 is a right hand elevation thereof.

Broken lines showing the neck finish are for the purpose of illustrating the environment of use.

FIG.1

FIG.3

FIG.2
